UNITED STATES PATENT OFFICE

JOSEPH BACHNER, OF NEW YORK, N. Y.

ALARM-WATCH.

SPECIFICATION forming part of Letters Patent No. 254,901, dated March 14, 1882.

Application filed August 1, 1881. (No model.)

To all whom it may concern:

Be it known that I, JOSEPH BACHNER, a subject of the Emperor of Russia, residing at New York, in the county and State of New York, 5 have invented new and useful Improvements in Alarm-Watches, of which the following is a specification.

This invention relates to alarm attachments for watches; and it consists in the combination 10 of an anvil on the rim of the watch-case for the reception of a percussion-cap, a hammer hung by an interior pivot to the case-rim, and having its outer end adapted to strike the anvil, a hammer-spring on the interior of the case-rim, 15 an index-wheel on the arbor of the hour-hand, carrying a trip-pin, and a hammer-lock mechanism adapted to be actuated by the trip-pin for releasing the hammer. The hammer-lock mechanism is composed of a dog engaging the 20 hammer and a trigger engaging the dog, the trigger being the part which is actuated by the trip-pin of the index-wheel.

This invention is illustrated in the accompanying drawings, in which Figure 1 represents a face view. Fig. 2 is a longitudinal section in the plane of the line x x , Fig. 3. Fig. 3 is a central cross-section.

Similar letters indicate corresponding parts.

The letter A designates the rim of the watch-case; B, the anvil; C, the hammer; D, the hammer-spring, and E the index-wheel. F designates the dog, and G the trigger, composing the hammer-lock mechanism.

The anvil B is constructed with a flange, o, 35 whereby it is secured to the case-rim A, to project on the exterior thereof, the shape of the anvil being such as to adapt it for receiving a percussion-cap.

The hammer C is hung to the case-rim by a 40 pivot, b, interior thereof, and the outer end or portion of the hammer is in a concentric line with the anvil B, so that it is adapted to strike the anvil.

The hammer-spring D is secured to the interior of the case-rim, and it acts on the tail end 45 of the hammer C with a tendency to force its outer end against the anvil.

The index-wheel E is constructed with a hub, s, whereby it is mounted on the arbor H of the 50 hour-hand I, and it revolves therewith, like the hour-hand, by frictional contact, so that the

index-wheel is capable of motion independently of the hour-hand and arbor. On the hubs of the index-wheel is secured its trip-pin t, Fig. 2, projecting therefrom in a radial direction; but this 55 pin can also be secured to the back of the wheel.

The trigger G swings on a pivot, i, and its one end lies in the path of the trip-pin t, so as to be actuated thereby, while its opposite or tail end lies next to a lug, n, formed at one end 60 of the dog F, the other end of the dog having a nose, u, for engaging the hammer C at its tail end, where the hammer is provided with a toe, u'.

The dog F and trigger G are arranged on 65 opposite sides of the plate J of the watch, and the lug n of the dog projects through a slot, k, in the plate, while the dog is subjected to the action of a spring, l, having a tendency to force the lug to the outer end of the slot. When the 70 hammer C is retracted the toe u' rides past the nose u of the dog and takes its place thereon, while the lug n of the dog is at the same time forced against the tail end of the trigger G, as shown in Fig. 1. If the trigger G is now actuated and displaced by the trip-pin t, it releases 75 the dog, and the latter in turn releases the hammer, allowing it to follow the action of its spring and strike the anvil, so that if a percussion cap has been previously placed on the anvil the cap is exploded, thus sounding an alarm. 80

On the face of the index-wheel E are marked figures corresponding to those of the watch-dial, as shown in Fig. 1, and the trip-pin t is set to such a position relatively to such figures 85 that if the index-wheel is turned forward to bring that figure thereof representing the hour at which it is desired to sound the alarm opposite or below the hour-hand I the trip-pin will actuate the trigger G at that hour. In 90 other words, the position of the trip-pin t is such that if the figure 12 of the index-wheel is brought under the hour-hand at 12 o'clock the trip-pin will have just passed beyond the trigger.

It should be remarked that other lock mechanism can be substituted for that shown without departure from my invention. 95

What I claim as new, and desire to secure by Letters Patent, is—

1. The combination, substantially as hereinbefore set forth, of the anvil on the rim of the watch-case for the reception of a percussion- 100

cap, the hammer hung by an interior pivot to the case-rim, and having its outer end adapted to strike the anvil, the hammer-spring on the interior of the case-rim, the index-wheel on the arbor of the hour-hand carrying a trip-pin, and the hammer-lock mechanism adapted to be actuated by the trip-pin for releasing the hammer.

2. The combination, substantially as hereinbefore set forth, of the anvil on the rim of the watch-case for the reception of a percussion-cap, the hammer hung by an interior pivot to the case-rim, and having its outer end adapted

to strike the anvil, the hammer-spring on the interior of the case-rim, the dog engaging the hammer, the trigger engaging the dog, and the index-wheel on the arbor of the hour-hand carrying a trip-pin adapted to actuate the trigger.

In testimony whereof I have hereunto set my hand and seal in the presence of two subscribing witnesses.

JOSEPH BACHNER. [L. S.]
